United States Patent Office

Des. 177,446
Patented Apr. 10, 1956

177,446

HANDBAG OR SIMILAR ARTICLE

Gladys A. Utzinger, Casper, Wyo.

Application May 18, 1954, Serial No. 30,542

Term of patent 14 years

(Cl. D87—3)

The figure is a side elevation of a hand bag or a similar article embodying my new design, the ornamentation on the opposite side of the bag being identical to that disclosed.

I claim:

The ornamental design for a hand bag or similar article, substantially as shown and described.
